WILLIAM J. KARMIRE, OF SHELBYVILLE, INDIANA, ASSIGNOR TO EDWARD A. SWAIN, OF SHELBYVILLE, INDIANA.

JOINING-EQUALIZER FOR WOODWORKING.

1,401,787.

Specification of Letters Patent. Patented Dec. 27, 1921.

Application filed April 16, 1920. Serial No. 374,387.

To all whom it may concern:

Be it known that I, WILLIAM J. KARMIRE, a citizen of the United States, and a resident of Shelbyville, county of Shelby, and State of Indiana, have invented a certain new and useful Joining-Equalizer for Woodworking; and I do hereby declare that the following is a full, clear, and exact description thereof, reference being had to the accompanying drawings, in which like numerals refer to like parts.

This invention relates to the furniture art and in particular to means for forming and equalizing joints of wooden stock. The chief object of the invention is to construct a furniture leg or the like of a main body portion and secure to the same suitable facings or panel portions by an improved joint.

The chief feature of the invention consists in machining the base stock in such a manner that the facings to be secured thereto, when assembled and glued together, will form a tight joint in an improved manner. Other features of the invention are embodied in a machine for fashioning the stock base, said machine including numerous combinations which are new in the art.

The machine in particular is an adaptation of a milling machine or planer to a woodworking art.

In the drawings Figure 1 is an elevational view of the machine in position to begin fashioning the stock base. Fig. 2 is a plan view showing the completed stock base in full lines and the original stock base in dotted lines before the same has been reduced to the full line outline by the machine illustrated in Fig. 1. Fig. 3 is a plan view of the fashioned stock base with suitable side facings secured thereto and showing in particular the improved means for receiving the glue forced from the joint faces. Fig. 4 is an enlarged side elevation of the woodworking machine showing in particular the various cutting devices and means for maintaining and driving the same. Fig. 5 is a partial view of the "squaring" mechanism, showing the same in the extreme positions. Fig. 6 is a semi-diagrammatic plan view of the carriage controlling mechanism. Fig. 7 is an elevational view of the same.

In Figs. 2 and 3 there is illustrated a stock portion 10, the original dimensions thereof being indicated by the dotted lines 11 of Fig. 2. The base 10 is provided with two

projecting tenons 12 and 13 respectively and a slot or groove 14, the same being in parallel relation. As shown in Fig. 3 suitable facing portions 15 and 16 are respectively provided with mortise grooves 17 and 18, the same being adapted to receive the tenons 12 and 13 respectively. The abutting edges 19 of the adjacent facing portions 15 and 16 form a close and equal joint, and when positioned in this manner upon the base stock 10 form with the groove 14 a suitable glue receiving slot 20 extending substantially parallel with said joint. In this manner, glue which has been exuded from the adjacent joint surfaces between the members 16 and 10, 15 and 10 and 15 and 16 respectively is received by the slot 20 formed at the junction of these three members 10, 15 and 16.

The means for forming the various slots and tenons of the stock base 10 is shown best in Fig. 4. In the drawings 21, indicates the bed of the machine similar to a planer or shaper, the same being provided with a reciprocatorily mounted carriage member 22, the same being adapted to support a head stock 23 and a tail stock 24. The head stock 23 carries the stock supporting spindle 25, and the tail stock 24 supports the stock supporting spindle 26 respectively. As shown clearly in Fig. 1 the rearward portion of the spindle 26 is cut away to form a rack portion 27, the same being slidably received by the tail stock head 28, the latter being slidably supported by the tail stock portion 24. The stocks 23 and 24 are shown clearly in Figs. 4 and 5 as formed of upwardly and outwardly extending bracket portions. Rotatably mounted within said head 28 adjacent the rack 27, and in mesh therewith, is a pinion member 29. To the projecting portion of the shaft 30, rigid with said pinion and by which the same is rotatably supported, is rigidly secured a weight supporting arm 31, to which is secured, in an adjusted position, the counterweight 32, and which is rocked or rotated by the arm 32a. With the foregoing construction the counterweight 32 always maintains, through the pinion 29 and the rack 27, the spindle 26 in engagement with the stock 10 so as to maintain pressure upon and quickly secure the same between said last mentioned spindle and the spindle 25.

To provide a greater range of adjustability, the tail stock 24 is preferably formed

in sections, and said sections adjustably secured together. In the present instance a plate 33 is suitably secured or formed integral with the carriage 22 and extends longitudinally therewith and upwardly therefrom, see Figs. 1 and 4. The plate 33 is provided with a longitudinally extending slot 34 adapted to receive a suitable tongue member 35 integral with the upper tail stock 10 portion 24. The plate 33 is provided with a plurality of bolt receiving holes 36 in spaced relation with each other. A plurality of bolt members 37 rigidly secure the tail stock 24 to the plate 33 in any one of the 15 adjusting positions.

The means for positioning the stock 10 between the spindles 25 and 26 so that the latter may grip and hold the same in the squared position comprises a plurality of 20 members as follows, and shown most clearly in Figs. 4 and 5. A horizontal supporting bar member 40 is slidably adjustable and rigidly supported at 41 upon the supporting bed 21. A pair of clamp members 42 are 25 adjustably secured in spaced relation with each other by the bolts 43 upon the supporting rod 40. Supported by the clamp members are a pair of rock shafts 44 upon which similar clamp members 45 are mounted. 30 Parallel rod members 46 are adjustably secured to the clamp members 45 by means of the adjusting bolts 47. Upon the upper ends of the rods 46 is similarly secured a pair of clamp members 48, adjustably secured by 35 means of the usual bolts 49. Pivotaly supported thereby, and the brackets 50 is a second bar member 51 parallel to the supporting bar member 40. The bar member 51 extends inwardly toward the machine and 40 toward the stock supporting spindle, and upon its outer end carries a positioning guide bracket, upwardly extending arm or standard 52 adjustably secured thereto by means of a bolt 53. Means for locking the foregoing 45 parallelogram comprises a pivoted lever 54 suitably connected to the parallelogram and counter-balanced by the counter weight 155 which also maintains the parallelogram or positioning device in the inoperative position, shown in Fig. 4, so that the forwardly 50 extending end of the rod 51 and the standard 52 will not interfere with the cutters operating upon the stock. When the parallelogram is operated by the lever 54 parts move from 55 the full line position shown in Fig. 4 to the dotted position shown in the same figure, which moves the parts shown in the full line position in Fig. 5 to the dotted line position shown in the same figure. It will be understood that the stock may be positioned upon 60 the bar 51 so that one face thereof rests upon the bar 51 and the adjacent face thereof abuts the standard 52, said standard extending at right angles to the arm 51. It will be 65 understood that the paralleling device de-

scribed is duplicated so that, as shown in Fig. 1, the stock 10 will be positioned exactly as desired so that when the spindles 25 and 26 engage the same said stock will be positioned and ready to be machined by the cutting means. 70

Herein and in the claims the paralleling means is called a "squaring" device but it will be understood that other suitable means may be used instead of the standards 52, so that irregularly shaped stocks 10 may be centered for the spindles to engage the same and these means are considered the full equivalent of the "squaring" means described. 75

After the stock has been positioned between the spindles by means of the paralleling device described, the carriage 22 is reciprocated across the bed 21 by means comprised as follows. Upon the under face of 80 the carriage 22 is suitably secured a rack member 55, and rotatably supported by the bed 21 and meshing with the rack 55, is a reversible driving pinion 56 rotatable by the shaft 57, the same carrying upon one of its 90 outer ends a bevel pinion 58, the latter meshing with a similar pinion 59 carried by a vertical shaft 60. Upon the lower end of the shaft 60 is secured a bevel plate or gear 61 by which the carriage 22 is reciprocated 95 upon the bed 21, when meshing with either of the driving bevel pinions 62 and 63 rotatable by a shaft 64, the same carrying a pulley 65, whereby power is transmitted to the pinion 56. It will be understood that, 100 as shown in Fig. 4, both driving pulleys 62 or 63 may be out of mesh with the bevel gear 61, so that said carriage 22 will be stationary upon the bed 21. When the bevel pinion 62 is in mesh with the bevel gear 61, the carriage will move from one end of the bed to the other, and when the gear 61 is in mesh with the pinion 63, the carriage will move from the last mentioned end to the opposite end of the bed. 105

The means for alternately engaging either of said pinions 62 and 63 with the driving gear 61 comprises a supporting means 66 by which the shaft 64 is pivotally supported, as well as rotatably supported. It will, of course, be understood that instead of pivoting said pinions 62 and 63 into and out of mesh with gear 61, the same may be longitudinally slideable upon the shaft 64 and engageable alternately with the driving gear 61, as desired, by the usual mechanism associated therewith. In the present instance, however, the shaft is pivotally supported, and means are provided for rocking said shaft in either direction about the pivotal support 66 so as to engage the respective pinion with the driving gear 61. The means for tilting the shaft 64 in a direction to move the pinion 62 upwardly into engagement with the gear 61, comprises a shaft en- 110

115

120

125

130

gaging rocking member 70 suitably secured to a tilting lever or rod 71, pivotally supported at 72 upon the frame 21. The outer end of the tilting rod or lever 71 extends 5 substantially toward the center of the bed 21, and is provided with suitable engaging portions 73 by which the same may be normally tilted, when the operator's foot is placed thereon, to engage pinion 62 with the gear 61. Similarly the shaft engaging member 75, see Figs. 4 and 6, is suitably secured to a rocking lever 76 pivotally supported at 77 upon the bed 21. The opposite end of said rocking lever 76 is secured to a rod 177 10 which extends transversely of the bed 21, and is rocked by means of a lever 78 suitably connected to the lever 79, pivotally supported at 80 to the bed 21 by means of a connecting rod 81. Thus when the lever 15 79 is depressed by the operator's foot engaging thereon, the lever 78 actuates the transverse rod 177 and rocks the same to tilt the adjacent end of the rocking lever 76 downwardly through the mechanism 20 shown in Fig. 6. This raises the opposite end of said lever upwardly to place the bevel pinion 63 into engagement with the bevel gear 61, by tilting or rocking the shaft 64, which simultaneously disengages 25 the pinion 62 from the bevel gear 61 before the pinion 63 engages therewith. With the foregoing the carriage will not be reciprocated in either direction until either one of 30 said levers 73 or 79 is normally actuated by the operator.

Means are herein provided for automatically disengaging the respective bevel gears 62 and 63 from the gear 61, when the carriage is moved to the end of the desired reciprocal movement upon the bed 21. Said 40 means comprise suitable stop or limit lugs 85, see Figs. 1, 6 and 7, positioned at one end of the bed 21, and a similar lug 86 positioned at the opposite end of said bed. 45 In the present instance suitable supporting rods 87 and 88 respectively support the stop lugs 85 and 86, to which the same are adjustably secured by means of suitable adjusting bolts 89. A pair of transversely extending rods 90 and 91 are respectively connected to the limit rods 87 and 88, and upon one end thereof are secured the tripping rods 92 and 93 respectively connected to, and operated by, the travel limit actuating lugs 50 85 and 86 respectively. The end portions of said tripping rods are preferably curved outwardly and then backwardly toward the opposite end thereof to form a hook portion 94, the same adapted to engage one end 55 of the respective tilting rods 95 and 96 for tilting the respective levers 79 and 71 in a direction opposite to that heretofore described, so as to disengage the respective bevel gears 62 and 63 from engagement with 60 the driving gear 61.

Positioned upon the frame 21 are a pair of latching members 97, the same being engageable in the slots or notches 98 formed in each of said tilting rods or levers 95 and 96. The latching members 97 are held in engagement with the rods 95 and 96 by means of the spring members 99, and when either of said latching members 97 is in engagement with the notch 98, said rod will be maintained in an elevated position, 70 which is the equivalent of the operator maintaining the actuating portion of the respective tilting lever 71 or 79 in a depressed position. Said latch will maintain the rod 75 95 or the rod 96, since only one will be in engagement at any time, until the rod 95 or 96 is released from engagement with said latching member 97 by being actuated by the respective stop lugs through the hook portion 94 on the tripping rods 92 or 93. 80

With the foregoing mechanism the operator tilts the shaft 64 in the desired direction to engage the desired bevel pinion with the driving gear 61. Simultaneously therewith the respective rod 95 or 96 is elevated, and 90 is secured in the elevated position to maintain the respective pinion in engagement with the driving gear until the carriage is moved to engage the respective travel limit lugs 85 or 86. This automatically releases 95 the tilting rod 95 or 96 from engagement with the latching tooth and tilts the shaft 64 in an opposite direction to remove the driving pinion from engagement with the driving gear, but does not move the other 100 driving pinion into engagement with the driving gear. This semi-automatic arrangement permits the operator to position a new piece of stock at one end of the movement and to manually or automatically remove 105 the stock from the spindles when the carriage is at the other end of the movement. If desired, the respective reversing pinion may be replaced by suitable means such that the usual "quick return" movement of 110 said carriage may be secured.

Means are provided for automatically braking the driving gear 61 after the bevel gears 62 and 63 have been removed from engagement therewith. Said means comprises 115 a brake shoe 100, the same being suitably connected to a brake rod 101, one end of which is pivoted to a rocking lever 102 pivoted to the bed 21, and the opposite end of which is secured to an actuating rod 120 103, the opposite end of which in turn is suitably connected to one end of the transverse rod 90 which, it will be remembered, has its other end connected to the tripping rods 92 and is operated by the stop lug 125 85, through the medium of the sliding rod 87. Similarly the transverse rod 91 is connected at its other end to an actuating rod 104, the same being connected in turn to a pivoted lever or brake bar 105, which 130

in turn is adapted to actuate a brake shoe 106 by pressing the same against the bevel gear 61, as shown. Thus when either of the travel limit lugs 85 and 86 is actuated by 5 the carriage 22, the respective levers 79 and 71 will be oppositely tilted to disengage the respective pinion 63 or 62, and simultaneously therewith the respective brake shoes 100 and 106 will be applied to the 10 periphery of the driving gear 61 to stop the rotation thereof. In the present instance suitable spring means 107 have one end secured to the transverse rods 90 and 91 and the opposite ends secured to the bed 21. 15 The means for shaping the stock 10, while the same is being moved longitudinally upon the bed 21, comprises, in the present instance, three cutting members 110, 111 and 112, rotatably mounted upon the shafts 20 113, 114 and 115, the latter being rotated by means of belt pulleys 116, 117 and 118, or any other suitable rotating means. The belt pulleys are preferably employed since each of said cutters 110, 111 and 113 is 25 independently mounted upon the bed 21 and is also adjustably mounted thereon. As shown in Fig. 1, the respective cutter carriages 119 and 120, supporting the cutters 111 and 112, are slidably supported upon re- 30 spective carriages 121 and 122 and secured in adjustable position by suitable bolt means 123. The carriage members 121 and 122, see Fig. 1, are vertically adjustable upon and secured to the bed 21 by means of bolts 35 124 slidably in slots 125 formed in and upon the bearing blocks 126 upon the bed 21. Each cutter 111 and 112 is thus rigidly supported upon the bed 21 and is independently capable of horizontal and vertical adjust- 40 ment thereon. As shown clearly in Figs. 1 and 4, it will be noted that the cutters 111 and 112 are disposed at right angles to each other and are positioned adjacent each other. In the present instance the cutter 45 112 operates upon the stock 10 before the cutter 111 operates thereon. As shown in Fig. 4, the cutters 111 and 112 form the tenon faces of the stock 10, the cutter 111 forming the tenon 13 and the slot 14, while 50 the cutter 112 cuts the face adjacent the tenon 12 and forms the tenon thereon. The cutters 111 and 112 are provided with the notches 127 and 128 respectively, and the cutter 111 is provided with the cutting portion 129 to form the slot 14 in the stock 10. The cutters 111 and 112 cut the adjacent face in the manner described, while 55 the cutter 110 cuts the other two opposite adjacent faces of said stock face 10. 60 In the present instance the cutter 10 is substantially provided with a V-shaped cutting edge 130 which substantially cuts the two opposite adjacent faces of the base stock 10 to form a square corner, substantially

as shown in Figs. 2 and 3. When it is de- 65 sired to cut other shaped edges the cutters 110, 111 and 112 may be replaced with other suitable formed cutters.

In the present instance the cutter 110, the shaft 113 and pulley 116, in addition to being 70 supported in a manner similar to the carriages 119 to 122 inclusive, is also provided with a pivotal support 131, the same being rigid with the carriage 132. The carriage 132 is longitudinally adjustable upon the 75 carriage 133, which latter carriage is vertically adjustable upon the bed 21 in substantially the manner heretofore described. A flange base plate 134 is pivotally supported upon the pivot shaft 131 and is maintained in the adjusted position by means such as a C-clamp portion 135, herein shown formed integral with the end of the carriage 132. The C-clamp 135 is provided with a pair of axially aligned and oppositely 80 extending clamping bolts 136 and 137, which extend through said clamping members toward the flange plate 134 to engage thereon. Suitable nut means 138 and 139 lock said bolts in the clamping position to rigidly 85 clamp the base plate 134 and the supporting arm 140 in the adjusted position.

The cutters 110, 111, and 112, as shown clearly in Fig. 4, are rotatable and substantially surround said stock base 10. Since 95 said cutters are adjustably and independently mounted in three different transverse planes upon the bed of the machine, and since the cutters may be removed and other cutters substituted therefor which will cut 100 the stock base 10 in any desired manner, the machine will be able to receive stock of a great range in size and fashion the same in any desired manner.

After the cutters have suitably fashioned 105 the stock 10 and the work supporting carriage 22 has moved to the end of its travel upon the bed 21, the depending arm 32^a encounters an upwardly extending tripping bar or member 150. This bar or member 110 is adjustably positioned upon the bed 21 such that the bar engages the arm 32^a substantially at the same time the bed engages the limit lug 86. Upon engagement with the bar 150, the arm 32^a rocks the shaft 30 115 in opposition to the counterweight 32, which rotates the pinion 29. The pinion 29, through the rack 27, moves the spindle 26 longitudinally in the tail stock 24 to release the same from engagement with the 120 completed base stock 10.

It will be noted from Fig. 4 that the head and tail stocks extend upwardly and outwardly so that when the completed stock 10 is released, the same will fall into a suitable receptacle without falling upon the machine. 125

The machine is substantially semi-auto-

matic in its action, since it is desired to have the operator carefully position the stock, and then after the same has been fashioned by the cutters carefully remove 5 the same. For this reason the operation of throwing the mesh of the gears 62 and 63 into mesh with the driving gear 61 is manually performed.

While the invention has been described 10 in detail it will be understood that the same is not to be limited thereby since many modifications thereof, a few of which have been suggested, will suggest themselves to those skilled in the art, and all of said modifications are considered to be within the pur- 15 view of the foregoing invention, the scope of which is indicated by the following claims.

The invention claimed is:

20 1. In a machine for working wood and the like, the combination with a supporting bed, and a carriage mounted thereon, of a plurality of parallelogram centering means supported upon said bed and movable in 25 parallel planes transverse to said bed and carriage, and a single means for moving all of said parallelogram centering means into the centering position adjacent said carriage.

30 2. In a machine for working wood and the like, the combination with a supporting bed, and a carriage mounted thereon, of a plu-

rality of parallelogram centering means supported upon said bed and movable in parallel planes transverse to said bed and 35 carriage, a single means for moving all of said parallelogram centering means into the centering position adjacent said carriage, and means for normally maintaining said centering means in the non-centering 40 position.

3. In a machine for working wood and the like the combination with a supporting bed and a work supporting carriage slidably mounted thereon, of work supporting 45 means upon said carriage including a head stock and a tail stock and an elongated spindle associated with said head stock and at least equal in length to the length of the work, and a plurality of cutters mounted 50 adjacent said carriage and between the stocks and adapted to fashion substantially the entire circumference of the work when the carriage moves from one position upon the bed to the other position upon the bed, 55 said spindle and head stock being movable from a position adjacent the forward cutter away from the same until the spindle has passed through all of said cutters and the work has also passed therethrough. 60

In witness whereof, I have hereunto affixed my signature.

WILLIAM J. KARMIRE.
